UNITED STATES PATENT OFFICE

EDWARD LEE DUNN, OF EAST ORANGE, NEW JERSEY, ASSIGNOR TO OTIS ELEVATOR COMPANY, OF NEW YORK, N. Y., A CORPORATION OF NEW JERSEY

LOCKING MECHANISM

Application filed October 3, 1928. Serial No. 309,955.

The invention relates to locking mechanism for elevator hatchway doors and particularly to mechanism for interlocking the hatchway doors with the elevator car and with the control device for the car.

5 The invention is directed to locking mechanism of the above character primarily adapted for elevator systems in which a hand rope is provided for controlling the operation of the elevator car.

One feature of the invention resides in preventing the operation of the control device to start the elevator car unless all the hatchway doors are closed.

10 Another feature of the invention is to prevent the opening of any door unless the car is at the floor at which the door is located and the control device is in the off position.

Still another feature of the invention resides in doubly locking each door when the control device is in running position and the elevator car is away from the floor at which such door is located.

15 A fourth feature of the invention is the provision of locking mechanism which is of simple and rugged construction, cheap to manufacture, easy to install, and which is positive in operation.

A fifth feature of the invention resides in the provision of locking mechanism which may be used without alteration for either right- or left-hand doors.

Other features and advantages will become apparent from the following description and appended claims.

20 The invention will be described, by way of illustration, as embodied in a hand rope controlled elevator system in which the hatchway doors are vertically movable, although it is to be understood that this invention is equally applicable to horizontally sliding and other types of doors. A freight elevator installation in which the starting and stopping of the car is controlled by a hand rope and in which vertically movable hatchway gates are provided for closing the hatchway openings at the various landings is typical of such a system and the invention is illustrated as applied to this type of installation.

25 The invention involves a member connected

to the controlling mechanism for the elevator car, a member connected to the hatchway door, and a locking device associated with both of said members in such manner that movement of the first member is prevented by the cooperation of the locking device and the second member to lock the controlling mechanism in off position when the hatchway door is open, and that movement of the second member is prevented by the cooperation of the locking device and the first member to lock the hatchway door in closed position when the controlling mechanism is moved to a start position; and further involves latching means for cooperating with said locking device to prevent movement of the first member and thus lock the hatchway door in closed position when the elevator car is away from the landing at which the door is located, regardless of whether or not movement of the first member is prevented by the cooperation of the locking device and the second member. The invention also involves operating all of the second members by common actuating means so as to effect the locking of all hatchway doors whenever the control mechanism is in either start position.

25 In the drawings:—

Figure 1 is a schematic representation of a hand-rope-controlled elevator system embodying the invention;

Figure 2 is an elevation of the locking mechanism which is provided at each floor with portions of the cover removed to illustrate certain structural details;

Figure 3 is a sectional view of the locking mechanism taken along the line 3—3 of Figure 2;

Figure 4 is a sectional view of the locking mechanism taken along the line 4—4 of Figure 2;

Figure 5 is a fragmentary view of the locking mechanism as applied to the vertically sliding hatchway gate of Figure 1, with portions broken away to illustrate certain structural details;

Figure 6 is a sectional view taken along the line 6—6 of Figure 5, and illustrates a portion of the elevator car with the car cam applied thereto; and

Figure 7 illustrates the adaptation of the locking mechanism to a collapsible hatchway gate, parts being broken away to illustrate certain structural details.

Referring to Figure 1, the elevator shaft is indicated by the numeral 10, the car by the numeral 11 and the hoisting motor and apparatus for operating the car within the shaft by the numeral 12. A reversing-switch 13 is provided for controlling the operation of motor 12, the switch being operated from the car by a hand rope 14. A turnbuckle 15 is inserted in hand rope 14 for maintaining the rope taut between controller sheave 16 and sheave 17.

A centering rope 18 with a weight 22 secured at one end thereof is provided for the hand rope 14, the centering rope being operably connected to hand rope 14 by means of chains 20. Chains 20 are held in their proper positions relative to hand rope 14 by means of the stop balls 21. By this construction centering rope 18 and weight 22 are always moved upwardly from their neutral position regardless of the direction that the hand rope 14 is moved from its neutral position. Thus, the tendency of the centering rope and weight is to return the controlling mechanism to neutral, or center.

At each floor of the installation a locking mechanism 23 is provided which is operably connected to this centering rope and operably connected to the adjacent hatchway gate.

The construction of locking mechanism 23 is clearly shown in Figures 2 to 6 inclusive. According to the preferred arrangement, a base 24 is provided with holes 25 through which base supporting screws may be inserted for securing the base to a wall of the shaft. A segment or quadrant 26 is pivotally mounted upon base 24 by means of a pin 27 which is securely riveted to the base. A cotter pin 19 serves to hold segment 26 in place. Segment 26 is provided with two operating faces 28 and 30, and with a projecting lug 31, and also with a grooved or recessed portion 32 to allow the segment to be thrown to any position without it interfering with or engaging centering rope 18. Base 24 is suitably recessed at 29 to allow the segment 26 to freely swing from one to the other of its extreme positions, the ends of the recess forming stops therefor. Rigidly secured to base 24 are two

pairs of supporting arms 33, upon each pair of which a latch or lever 34 is pivotally mounted by means of a pin 35. Each of the latches 34 is provided with an enlarged portion 36 at its end adjacent segment 26 for engaging the projecting lug 31 of this segment. A compression spring 37 is provided for each latch 34 for urging the latch in such a direction that its enlarged portion 36 is held in engagement with segment 26. Each latch 34 is further provided with a cam engaging

portion 41 at its end remote from segment 26. A longitudinal semi-cylindrical recess 43 is formed within base 24 upon one side of segment 26. A similar longitudinal semi-cylindrical recess 44 is formed within base 24 upon the other side of segment 26.

A base cover 45 is provided for base 24, which cover is provided with an opening 46 through which enlarged portions 36 may pass as they are caused to move outwardly. A longitudinal semi-cylindrical recess 48 is formed within the cover 45 to cooperate with semi-cylindrical recess 43 formed within base 24 thereby forming a longitudinal cylindrical passage 50 on one side of segment 26. A similar longitudinal semi-cylindrical recess 51 is formed within the cover 45 to cooperate with semi-cylindrical recess 44 formed within base 24 thereby forming a longitudinal cylindrical passage 52 on the other side of segment 26. Screws 53 serve to securely fasten cover plate 45 to base 24.

Each locking mechanism 23 is so placed at the floor that centering rope 18 passes down through cylindrical passage 52. At each floor a pipe or cylindrical rod 54 is securely fastened to centering rope 18 by means of a rope pin 55 and a rope clamp 56 so that the pipe 54 passes up through cylindrical passage 52 with the rope 18 upon vertical movement of the rope. Each hatchway gate 57 is provided with an extension arm 58 upon which arm a pipe or cylindrical rod 60 is secured. As gate 57 is moved into open position, pipe 60 is mounted to pass up through cylindrical passage 50. Hatchway gate 57 is also provided with a door rope 61 and with a counterweight 69 attached to the end of the door rope.

The elevator car 11 is provided with a cam 67, as may be seen in Figures 1 and 6, this cam being positioned to engage portions 41 of latches 34 in the locking mechanism 23 of each floor when the elevator car is opposite that floor. In so doing, cam 67 depresses portions 41 and lifts enlarged portions 36 out of the path of movement of lug 31.

The operation of the mechanical interlocking mechanism is as follows:

Assume that elevator car 11 is stopped at a floor and that the hatchway gate at that floor is open, as shown in Figure 1. The parts of locking mechanism 23 at that floor are then in the positions shown in Figures 2 and 3. Pipe 54 is in its lowest position as hand rope 14, and thus centering rope 18, are in their neutral position. Pipe 60 is in its highest position as hatchway gate 57 is open. Latches 34 are out of engagement with segment 26 as car cam 67 is in engagement with portions 41 of the latches. Segment 26 is in one of its extreme positions, having been moved to that position by pipe 60 when the pipe was moved to its upper position by shaft door 57. Pipe 60 securely holds seg-

ment 26 in the position shown, thus securely locking centering rope 18 in its lowest position and thereby preventing movement of hand rope 14 in either direction. Any attempt to move hand rope 14 immediately brings pipe 54 into contact with operating face 30 of locked segment 26. Before any movement of hand rope 14 is possible hatchway gate 57 must be closed. As hatchway gate 57 is moved to its closed position, pipe 60 moves downwardly out of engagement with segment 26, thereby releasing the segment. Centering rope 18 is thus unlocked to permit movement of hand rope 14 when the hatchway gate is closed. When hand rope 14 is moved either in an up or a down direction depending upon which direction it is desired to move the car, centering rope 18 is moved upwardly by one of the chains 20. The rope takes with it pipe 54 which engages operating face 30 of segment 26 causing the segment to swing to its other extreme position. Segment 26 is then securely locked in that position by pipe 54, thus securely locking hatchway gate 57 in its closed position when the controlling mechanism is actuated to move the car. The parts are then in the position shown in Figure 5. Any attempt to open hatchway gate 57 is prevented by the immediate engagement of pipe 60 with operating face 28 of secured segment 26.

As car 11 moves from the floor, cam 67 disengages portions 41 of latches 34, whereupon enlarged portions 36 of the latches move into engagement with segment 26 under the influence of springs 37. Movement of segment 26 is then impossible, since its lug 31 abuts enlarged portions 36 of latches 34. This is illustrated by the dot-and-dash outline in Figure 3. Shaft door 57 is therefore doubly locked in closed position when car 11 is in motion away from the landing, since it is locked by the segment and pipe 54, and by the segment, lug 31 and latches 34.

When the hand rope is actuated to bring the car to rest at a landing, the centering rope drops to its lowest position, carrying with it each of the pipes 54. The cylindrical surface of each pipe no longer abuts the operating face 30 of the corresponding segment. Hence, one of the locks for each segment 26 is released. As the car nears the landing, the car cam 67 depresses portion 41 to release the latches 34 from the lug 31 of the locking mechanism of that landing thereby completely unlocking that hatchway gate. The hatchway gates for all the other landings remain locked, however, as the latches 34 of the locking mechanisms for such landings still engage their respective lugs 31. Thus, as only one gate at a time can have its latches 34 released, only one gate may be opened at a time, that gate being for the landing at which the car is stopped.

In Figure 7 the locking mechanism is shown

in an installation in which a collapsible hatchway gate 62 is used. The only difference in applying the interlocking system to this installation over that shown in Figures 5 and 6 is the manner of connecting pipe 60 to the door. A pipe supporting arm 63 is secured to one of the cross-bars of the gate above the interlock mechanism and is connected to pipe 60 by means of a connecting link 64. Connecting link 64 passes through annular recessed portion 32 of segment 26 so that it may freely move within passage 50 without interfering with the action of the segment.

The figures illustrate the interlocking system as applied to an elevator system in which the hand rope control, the centering rope, and the pipe 60 for the gate are on the right-hand side of the hatchway openings; that is, pipe 60 moves through longitudinal passage 50, and centering rope pipe 54 moves through longitudinal passage 52. If the elevator system is so constructed that the hand rope control and the centering rope are on the left-hand side of the hatchway, it is to be noted that the same locking mechanism 23 may be used, without any changes or alterations, for pipe 54 may move through longitudinal passage 50 and pipe 60 through longitudinal passage 52 and the operation of the locking mechanism 23 will not be changed.

Although the interlock has been illustrated with two latches 34, only one may be used if desired, for the operation will be the same with either one or two latches. The use of two latches, however, adds to the safety of the device. It may happen that a person may wish to open a hatchway gate other than the gate opposite to which the car has stopped, and endeavor to do so by manually depressing portions 41 of the latches and thereby release the segment that locks the gate. A person cannot manually release the segment and open the shaftway gate when two latches are employed since it requires both hands to release both latches.

In the event that a centering rope should not be provided for the hand rope control mechanism of the elevator, it is to be understood that a rope may be secured to the hand ropes in a manner similar to the arrangement of a centering rope; or that, if the control mechanism be of some other type, a rope or other device may be suitably arranged so that, upon the operation of the controlling device to either start position, the rope or other device is moved in one and the same direction to cooperate with the locking mechanisms in a manner similar to that described for a centering rope.

As many changes could be made in the above construction and many apparently widely different embodiments of this invention could be made without departing from the scope thereof, it is intended that all matter contained in the above description or

shown in the accompanying drawings shall be interpreted as illustrative and not in a limiting sense.

What is claimed is:

5. An interlock for a hatchway door and the controller of an elevator system comprising, a member secured to said hatchway door, a member operatively connected to the controller, and means to lock either one of said members by the movement of the other, said means including a device cooperating with both of said members, and also including the member that is moved. 70
10. In an elevator system in which a hand rope is provided for controlling the operation of the elevator car and in which a hatchway door is provided for a landing, a locking member for said door, means cooperating with said locking member to lock said door when the car is away from said landing, and means operated by said hand rope upon movement thereof to start the car to cooperate with said locking member to lock said door, both of said means being adapted to cooperate with 80 said locking member simultaneously when the car is away from said floor and said hand rope is in running position to doubly lock said door. 85
15. In an elevator system in which a hand rope is provided for controlling the starting of the elevator car and in which a hatchway door is provided for a landing, mechanism for interlocking said hand rope and said hatchway door to prevent operation of said hand rope to start the car when the door is open, said mechanism comprising, a member connected to said hand rope to be moved thereby upon operation of said hand rope to start the car, securing means operable to prevent said motion of said member, and means operable by said door upon opening thereof to positively operate said securing means to lock said hand rope against operation. 90
20. In an elevator system in which controlling mechanism is provided for controlling the movement of the elevator car and in which a hatchway door is provided at each of a plurality of landings; door locking means for each of said hatchway doors, each locking means comprising, a door member secured to the corresponding door, a lock member movable into position to obstruct the door opening movement of said door member, and latching means operable upon movement of the elevator car from the landing at which the door is located and continuously operable while the elevator car is away from such landing, to prevent movement of the lock member therefor from said obstructing position; means operable upon the arrival of the elevator car at such landing to release the latching means for said door and thereby permit the removal of the lock member from the obstructing position and consequently 95
25. permit the door-opening movement of said door member; auxiliary latching means for each lock member operable to prevent movement of the lock member from its obstructing position; and common mechanical actuating mechanism for all of said auxiliary latching means actuatable by said controlling mechanism upon movement thereof to start the car to operate all of said auxiliary latching means to prevent movement of their respective lock members. 100
30. In an elevator system in which control mechanism is provided for controlling the operation of the elevator car and in which a hatchway gate is provided at each of a plurality of landings; mechanism for interlocking said control and said gates, each interlock mechanism comprising, a member movable by the corresponding gate upon opening thereof, a member adapted to be moved in one and the same direction upon operation of said control mechanism from off position into either starting position, a member associated with both of said other members and positioned to be moved by said second mentioned member, upon movement thereof as a result of the operation of said control mechanism to either start position, into such cooperative relation with said first mentioned member and to be maintained in such relation by said second mentioned member as to prevent movement of said first mentioned member and thus lock said gate, said second mentioned member, upon return of said control mechanism to off position, moving to release said third mentioned member and thereby release the first mentioned member, unlocking said gate; and means common to all of said interlock mechanisms and operable by said control mechanism, upon operation thereof from off position into either start position, to cause movement of all of said second mentioned members into locking relation with their respective first mentioned members. 105
35. In an elevator system in which control mechanism is provided for controlling the operation of the elevator car and in which a hatchway gate is provided at each of a plurality of landings; mechanism for interlocking said control mechanism and said gates, each interlock mechanism comprising, a member movable by the corresponding gate upon opening thereof, a member adapted to be moved in one and the same direction upon operation of said control mechanism from off position into either starting position, a member associated with both of said other members and positioned to be moved by said second mentioned member, upon movement thereof as a result of the operation of said control mechanism to either start position, into such cooperative relation with said first mentioned member and to be maintained in such relation by said second mentioned member as to prevent movement of said first mentioned member and thus lock said gate, said 110

- second mentioned member, upon return of said control mechanism to off position, moving to release said third mentioned member and thereby release the first mentioned member, unlocking said gate; means common to 5 all of said interlock mechanisms and operable by said control mechanism, upon operation thereof from off position into either start position, to cause movement of all of 10 said second mentioned members into locking relation with their respective first mentioned members; and mechanism for each gate for locking said third mentioned member for that gate when the car is away from the landing 15 at which such gate is located, regardless of whether or not said gate is locked by the second mentioned member of the interlock mechanism for such gate.
7. In an elevator system in which control 20 mechanism is provided for controlling the operation of the elevator car and in which a hatchway gate is provided at a landing; mechanism for interlocking said control mechanism and said gate comprising, a member 25 movable by the gate upon opening thereof, a member movable in one and the same direction by said control mechanism upon operation thereof from off position into either starting position, a member associated with 30 both of said other members and positioned to be moved by said second mentioned member, upon movement of said control mechanism to a start position, into such position with respect to the first mentioned member 35 and to be maintained in such position by said second mentioned member as to prevent movement of said first mentioned member and thus lock the gate, said second mentioned member, upon return of said control mechanism to off 40 position, returning to position to release said third mentioned member and thereby release the first mentioned member, unlocking the gate; and mechanism cooperating with said third mentioned member to prevent movement 45 of said first mentioned member and thus lock the gate when the elevator car is away from said landing, regardless of the position of the control mechanism.
8. In an elevator system in which control 50 mechanism is provided for controlling the operation of the elevator car and in which a hatchway gate is provided at a landing, mechanism for interlocking said control mechanism and said gate comprising, a member 55 movable by the gate upon opening thereof, a member movable in one and the same direction by said control mechanism upon operation thereof from off position into either starting position, a member associated with 60 both of said other members and positioned to be moved by said second mentioned member, upon movement of said control mechanism to a start position, into such position with respect to the first mentioned member 65 and to be maintained in such position by said second mentioned member as to prevent movement of said first mentioned member and thus lock the gates, said second mentioned member, upon return of said control mechanism to off position, returning to position to release said third mentioned member and thereby release the first mentioned member, unlocking the gate; and mechanism cooperating with said third mentioned member to prevent movement of said first mentioned member and thus lock the gate when the elevator car is away from said landing, regardless of the position of the control mechanism.
9. In an elevator system in which hand rope control mechanism is provided for controlling the operation of the elevator car and in which a hatchway gate is provided at a landing, mechanism for interlocking said hand rope control mechanism and said gate comprising, a member movable by the gate upon opening thereof, a rope connected to said hand rope control mechanism to be moved thereby in one and the same direction upon operation of said hand rope control mechanism from off position into either starting position, a member connected to said rope to be moved thereby, a pivoted segment associated with both members and positioned to be moved about its pivot by said rope operated member, upon movement of said hand rope control mechanism to a start position, into the path of movement of the first mentioned member and to be maintained in such position by said rope operated member, thereby preventing movement of said first mentioned member and thus locking the gate, said rope operated member, upon return of said hand rope control mechanism to off position, returning to position to release said segment and thereby release the first mentioned member, unlocking the gate.
10. In an elevator system in which hand rope control mechanism is provided for controlling the operation of the elevator car and in which a hatchway gate is provided at a landing; mechanism for interlocking said hand rope control mechanism and said gate comprising, a member movable by the gate upon opening thereof, a rope connected to said hand rope control mechanism to be moved thereby in one and the same direction upon operation of said hand rope control mechanism from off position into either starting position, a member connected to said rope to be moved thereby, a pivoted segment associated with both members and positioned to be moved about its pivot by said rope operated member, upon movement of said hand rope control mechanism to a start position, into the path of movement of the first mentioned member and to be maintained in such position by said rope operated member there- 110 115 120 125 130

by preventing movement of said first mentioned member and thus locking the gate, said rope operated member, upon return of said hand rope control mechanism to off position, returning to position to release said segment and thereby release the first mentioned member, unlocking the gate; mechanism operable in cooperation with said segment, when the elevator car is away from said landing, to prevent movement of said first mentioned member and thus lock the gate; and means for releasing said second mentioned mechanism from cooperative relation with said segment, when the car is at the landing, to permit movement of the first mentioned member and thereby permit opening of the gate provided the hand rope control mechanism is in off position.

11. In an elevator system in which hand-rope-operated control mechanism is provided for controlling the operation of the elevator car and in which a hatchway gate is provided at a landing; mechanism for interlocking said hand rope control mechanism and said gate comprising, a pair of guideways arranged in the hatchway adjacent said gate, a rod member secured to the gate for movement in one of said guideways upon opening of the gate, a centering rope connected to said hand rope to be moved thereby in one and the same direction upon movement of said hand rope to operate said control mechanism from off position into either starting position, a rod member connected to said centering rope for movement in the other of said guideways upon operation of said control mechanism, a segment pivoted between said guideways and arranged to be moved about its pivot by said centering-rope-operated rod member, upon movement of said hand rope to operate said control mechanism to either start position, across said one guideway to obstruct the movement of the first mentioned rod member and to be locked in such obstructing position by said centering-rope-operated rod member, thereby preventing movement of said first mentioned rod member and thus locking the gate, said centering-rope-operated rod member, upon movement of said hand rope to restore said control mechanism to off position, returning to position to unlock said segment and thereby release the first mentioned rod member, unlocking the gate, and said first mentioned rod member moving said segment about its pivot, upon opening of the gate, across said other guideway to obstruct the movement of the centering-rope-operated rod member and locking said segment in such obstructing position, thereby preventing movement of said centering-rope-operated rod member and thus locking said control mechanism in off position; latches operable in cooperation with said segment when the elevator car is away from said landing to prevent movement of the first mentioned rod member, thus locking the gate; and a cam carried by the elevator car for releasing said latches from cooperation with said segment, when the car is at the landing, to permit movement of the first mentioned rod member and thereby permit opening of the gate, provided the hand-rope-operated control mechanism is in off position.

12. In an elevator system in which hand-rope-operated control mechanism is provided

for controlling the operation of the elevator car and in which a hatchway gate is provided at a landing; mechanism for interlocking said hand rope control mechanism and said gate comprising, a pair of guideways arranged in the hatchway adjacent said gate, a rod member secured to the gate for movement in one of said guideways upon opening of the gate, a centering rope connected to said hand rope to be moved thereby in one and the same direction upon movement of said hand rope to operate said control mechanism from off position into either starting position, a rod member connected to said centering rope for movement in the other of said guideways upon operation of said control mechanism, a segment pivoted between said guideways and arranged to be moved about its pivot by said centering-rope-operated rod member, upon movement of said hand rope to operate said control mechanism to either start position, across said one guideway to obstruct the movement of the first mentioned rod member and to be locked in such obstructing position by said centering-rope-operated rod member, thereby preventing movement of said first mentioned rod member and thus locking the gate, said centering-rope-operated rod member, upon movement of said hand rope to restore said control mechanism to off position, returning to position to unlock said segment and thereby release the first mentioned rod member, unlocking the gate, and said first mentioned rod member moving said segment about its pivot, upon opening of the gate, across said other guideway to obstruct the movement of the centering-rope-operated rod member and locking said segment in such obstructing position, thereby preventing movement of said centering-rope-operated rod member and thus locking said control mechanism in off position; latches operable in cooperation with said segment when the elevator car is away from said landing to prevent movement of the first mentioned rod member, thus locking the gate; and a cam carried by the elevator car for releasing said latches from cooperation with said segment, when the car is at the landing, to permit movement of the first mentioned rod member and thereby permit opening of the gate, provided the hand-rope-operated control mechanism is in off position.

In testimony whereof, I have signed my name to this specification.

EDWARD LEE DUNN.
